(57) **CLAIM**

The ornamental design for an anesthetic delivery device, as shown and described.

DESCRIPTION

FIG. 1 is a perspective view of an anesthetic delivery device showing our new design;

FIG. 2 is a front elevation view thereof;

FIG. 3 is a rear elevation view thereof;

FIG. 4 is a left-hand side elevation view thereof;

FIG. 5 is a right-hand side elevation view thereof;

FIG. 6 is a top plan view thereof; and,

FIG. 7 is a bottom plan view thereof.

The broken line showing of anesthetic delivery device is included for the purpose of illustrating portions of the "article" and forms no part of the claimed design.
